Patented Dec. 14, 1965

203,171

DENTAL CHAIR

Daryl Raymond Beach, Fushimi-ku, Kyoto, Japan, assignor to Kabushiki Kaisha Morita Seisakusho, Fushimi-ku, Kyoto, Japan, a corporation of Japan

Filed Mar. 19, 1964, Ser. No. 79,089

Term of patent 14 years

(Cl. D15—3)

FIG.1.

FIG.2.

Des. 203,171

PAGE 2

FIG.3.

FIG.4.

Fig. 5

FIGURE 1 is a perspective view of a dental chair, showing my new design;

FIGURE 2 is a side elevational view of a dental chair showing my new design therefor;

FIGURE 3 is a rear elevational view of a dental chair showing my new design therefor;

FIGURE 4 is a front elevational view of a dental chair showing my new design therefor; and

FIGURE 5 is an enlarged view from the upper rear corner of a dental chair showing my new design therefor and illustrating in greater particularity the details of the headrest.

I claim:

The ornamental design for a dental chair, as shown and described.
